UNITED STATES PATENT OFFICE.

CHARLES GARNISS, OF NEWPORT, RHODE ISLAND.

TOP.

1,355,601.

Specification of Letters Patent. Patented Oct. 12, 1920.

Application filed October 20, 1917. Serial No. 197,533.

To all whom it may concern:

Be it known that I, CHARLES GARNISS, a citizen of the United States, residing at Newport, in the county of Newport and State of Rhode Island, have invented certain new and useful Improvements in Tops, of which the following is a specification.

My invention relates to tops and particularly to improvements in tops of that class whose construction includes a spring adapted to be wound up and used to spin the top with.

Tops of the kind referred to have heretofore usually been constructed with a separable handle or stem by means of which the spring was wound up which was objectionable for the reason that the stem was separated from the body of the top each time the latter was spun so that it was frequently lost thus rendering the top useless. Another form of spring actuated top required the use of both hands in order to wind up the spring and spin it which was objectionable.

The object of my invention is to provide a spring actuated top wherein the mechanism for operating it is embodied and inclosed in the top. It is a further object of my invention to provide a top of this class which has no separable parts liable to become lost and which can be spun with one hand.

In the accompanying drawings:

Figure 1 is a side elevation of my improved top.

Fig. 2 is a section on line 2—2 of Fig. 1.

Fig. 3 is a section on line 3—3 of Fig. 2.

Fig. 4 is a perspective view of the ratchet member hereinafter described.

Having reference to the drawings, 1 is the body of my improved top, said body being in most part exteriorly cylindrical but with its lower end made conical to provide a point 2 on which it spins. This form of body is a feature of my invention of importance for the reason that it provides an exterior configuration which adapts the top for whipping. That is, after the top has been started spinning it may be kept in motion by striking it with the flexible lash 5 of a whip.

The body 1 is made with a chamber 2 within which is arranged a coiled spring 3 surrounding a stem or shaft 4 to which the upper end of said spring is attached by being inserted in a hole 5 formed transversely

through said stem. The lower end of the spring 3 occupies a recess 6 formed in body 1 at the bottom of chamber 2.

The upper end of the chamber 2 is closed by a disk 7 that is driven into a countersink 8 provided at the outer end of chamber 2 so that it is fixed rigidly and permanently in place. This disk 7 is made with a central aperture 9 through which the stem 4 extends loosely so that it is both rotatable and endwise movable. Surrounding the aperture 9 upon the under side of the disk 7 is a plurality of recesses 10 shaped to provide shoulders 11 that coöperate with a pin 12 projecting laterally from stem 4. The spring 3 is incorporated in the top under slight endwise compression so that it yieldingly urges the stem 4 upward with the pin 12 held against the inner side of the ratchet disk 7. At its lower end the stem 4 projects into a centrally disposed recess 13 within which it is free to rotate and also move endwise to a limited extent.

My improved top is operated as follows: The spring 3 is wound up by rotating the stem 4 while the body 1 is held immovable, the endwise thrust of the spring causing the pin 12 to engage the ratchet disk or member 7 each time the stem 4 is turned to hold said spring against unwinding. When the spring is wound up sufficiently the operator, holding the top with one hand by means of the upper outer end of the stem 4, strikes the point of the top upon the floor, ground or other surface, at the same time pushing downward on the stem sufficiently to disengage the pin 12 from the ratchet disk 7 whereupon the spring quickly unwinds carrying the body 1 with it. For an instant after disengaging the pin 12 from the ratchet disk 7 the operator maintains his hold upon the stem 4 in order to hold the latter against rotating while the spring is unwinding and rotating the body 1. He should, however, use care to release the stem 4 before the spring is fully unwound otherwise the motion initiated by the release of the spring will be arrested.

As will be clear the top is started spinning in a right hand direction by the spring 3 so that after set in motion it can be whipped by means of a whip manipulated by the right hand.

The top above described is simple in construction, inexpensive to build and has no

separable parts, all of the elements thereof being permanently connected and inseparable.

The body 1 and stem 4 may be made from wood, metal or any other suitable material.

What I claim is:

1. A top of the character described comprising a hollow body; a stem mounted within said body with provision for rotation and endwise movement relatively thereto, one end of said stem extending outwardly beyond the top of said body; a laterally extending projection on said stem and within said body; a series of ratchet teeth on the body adapted to be engaged by said projection, and a single spring within said body having one end thereof connected with the body and the opposite end thereof connected with said stem, said spring serving both to yieldingly urge the stem endwise in a direction to hold said projection in engagement with the ratchet teeth and also to rotate said body when said projection is disengaged from said ratchet teeth by endwise movement of said stem against the pressure of said spring.

2. A top of the character described comprising a hollow body made exteriorly cylindrical and having a blunt conical lower end; a stem mounted within said body with provision for rotation and endwise movement relatively thereto, one end of said stem

extending outwardly beyond the top of said body; a laterally extending projection on said stem and within said body; a series of ratchet teeth on the body adapted to be engaged by said projection, and a single spring within said body having one end thereof connected with the body and the opposite end thereof connected with said stem, said spring serving both to yieldingly urge the stem endwise in a direction to hold said projection in engagement with the ratchet teeth and also to rotate said body when said projection is disengaged from said ratchet teeth by endwise movement of said stem against the pressure of said spring.

3. A top of the character described made with a hollow body; a coiled spring arranged within said body; a rotatable and endwise movable stem extending into said body and through said spring to which one end of the latter is connected so that the spring acts endwise and rotatively upon said stem, and means for holding the body and stem against relative rotary movement when the spring is wound up, said means being caused to free the body by endwise movement of the stem against the pressure of the spring.

In testimony whereof I have affixed my signature.

CHARLES GARNISS.
